Inventor,
Derbin Shutt Myers
By *At. N. Franklin* *Atty.*

UNITED STATES PATENT OFFICE.

DERBIN SHUTT MYERS, OF EVANSVILLE, INDIANA.

CONCEALED HINGE.

Application filed April 23, 1928. Serial No. 272,393.

The object of this invention is the provision of an improved hinge which can be readily applied to, or removed from, the parts it is intended to connect, with a minimum use of tools and without requiring extra bolts, screws, or other fastenings to be employed and will, when in position, be substantially concealed. The hinge is particularly adapted for use on water closet seats but is adapted for use on stoves, furniture, or anywhere that the parts to be hinged are of sufficient thickness to accommodate the hinge according to the construction and manner of use hereinafter set forth.

15 In the accompanying drawings:

Figure 1, is a detail vertical section showing the hinge applied to the bowl and seat of a water closet, dotted lines representing the seat in raised position;

20 Fig. 2, is a similar view, showing the manner in which the hinge is applied to the seat;

Fig. 3, is a detail side elevation of the detachable hooded hinge member; and

25 Fig. 4, is a plan view thereof.

The rear of the water closet seat appears at 1 and the rear of the bowl at 2.

My improved hinge comprises but three parts, namely, the hinge pillar proper 3, 30 the attachable and detachable hood-like hinge member 4, the hinge pin 5, said member 4 fitting and cooperating with the walls of the cavity or recess 6 in the underside of the seat 1 to secure the hinge member 4 in 35 position.

The hinge pillar 3 is of goose-neck shape so that it may extend up within the hinge member 4 to afford proper clearance to enable the seat 1 to swing properly. The 40 pillar 3 has any suitable integral bolt 7, provided with a nut, for attaching it to the rear end of the water closet bowl 2.

The hinge-member 4 may be made as a stamping, being of springy metal, of elongated shape, having sides 8, a top 9, an open rear end 10, and a front end comprising a locking tongue or latch 11 and a releasing finger-piece 12 which projects downwardly below the seat 1 when the hinge is in position, to enable it to be manipulated.

45 The member 4 is open at its bottom to receive the upper part of the goose-neck 3.

The locking tongue 11 and finger-piece 12 are defined by the slits 13, these parts being 50 free and resilient. The ends of the sides 8

are rounded at 8' to fulcrum on the rounded end 8" of the cavity 6 (Fig. 2).

There is a pin 5 serving as a pintle to connect the goose-neck 3 to the member 4.

Assuming that the members 3 and 4 are 60 connected by the hinge pin or pintle 5, the hinge may be attached to the seat 1 by pressing the member 4 into the cavity 6, using the parts 8', 8", as a fulcrum, whereupon the tongue 11 will snap into an offset notch 14 65 and lock the member 4 in position. As said member 4 snugly fits the walls of cavity 6, the hinge is securely connected to the seat 1.

To release the hinge so that it may be detached from the seat 1, pressure is applied to 70 the finger 12 to withdraw the locking tongue or latch 11 from the notch 14, whereupon the parts will fulcrum at 8', 8", as shown in Fig. 2.

As no tools or extra fastenings are required other than to provide the recess 6 and the hole for the post 7, the labor involved in putting on, or removing, the hinge is trifling.

75 My hinge is well adapted for use on water closet seats because the area of the exposed parts is small and corrosion is, therefore, minimized; furthermore, the concealment of the parts, enables the seat to present a neat appearance.

80 What I claim is:

1. In a hinge, the combination of hinge members, one of which is of substantially "goose-neck" shape and has means for its attachment to one of the parts to be hinged 90 together, the other member being of hooded form and receiving, and pivoted to, the first-named member, said hooded member being adapted for reception within a cavity provided in the other of the parts to be hinged 95 together, there being provided means for automatically securing the hooded member within the said cavity when placed therein.

2. In a hinge, the combination with parts one of which has a cavity provided with a 100 notch, of two hinge members, one of which is connected to one of said parts, the other member being hinged to the first-named member and contained within the cavity and having a releasable latch engaged with said 105 notch to secure the member in said cavity.

3. A hinge comprising a goose-neck member provided with means for its attachment to one of the parts to be hinged together, and an elongated hood-like member receiv- 110

ing, and hinged to said goose-neck member, said hook-like member being provided with a combined resilient latch and finger-piece, said latch being adapted to secure the hood-like member to the other of the parts to be hinged together and arranged for release by the manipulation of said finger-piece.

4. The combination with two parts, of means for hinging them together comprising a goose-neck hinge member, a hood-like member having a rounded fulcrum part and which receives, and is hinged to the goose-

neck member, and is provided with a combined locking spring-tongue and releasing finger, one of said parts having a cavity provided with a rounded part serving as a fulcrum-seat for the rounded part on the hood-like member, said cavity detachably receiving the hood-like member and provided with a notch to receive the locking spring tongue, the releasing finger then being positioned for manipulation.

In testimony whereof I affix my signature.
DERBIN SHUTT MYERS.
